US0D1103961S

(12) **United States Design Patent** (10) **Patent No.:** **US D1,103,961 S**
(45) **Date of Patent:** **** Dec. 2, 2025**

(54) **EARPHONE**

(71) Applicant: **Anker Innovations Technology Co., Ltd.**, Changsha (CN)

(72) Inventors: **Hangyu Li**, Shenzhen (CN); **Zheng Wei**, Shenzhen (CN)

(73) Assignee: **Anker Innovations Technology Co., Ltd.**, Changsha (CN)

(**) Term: **15 Years**

(21) Appl. No.: **29/919,085**

(22) Filed: **Dec. 1, 2023**

(30) **Foreign Application Priority Data**

Jun. 1, 2023 (CN) 202330333045.0

(51) **LOC (15) Cl.** **14-01**

(52) **U.S. Cl.**

USPC **D14/223**

(58) **Field of Classification Search**

(57) **CLAIM**

The ornamental design for an earphone as shown and described.

DESCRIPTION

FIG. 1 is a front-top perspective view of an earphone showing our new design;

FIG. 2 is a rear-bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the earphone that form no part of the claimed design.

1 Claim, 8 Drawing Sheets
